Attorney

UNITED STATES PATENT OFFICE.

SALVATORE FERRAGAMO, OF SANTA BARBARA, CALIFORNIA.

TURNBUCKLE.

1,393,614.

Specification of Letters Patent. Patented Oct. 11, 1921.

Application filed February 4, 1921. Serial No. 442,469.

To all whom it may concern:

Be it known that I, SALVATORE FERRAGAMO, a citizen of Italy, residing at Santa Barbara, in the county of Santa Barbara and State of California, U. S. A., have invented certain new and useful Improvements in Turnbuckles; and I do hereby declare the following to be a full, clear, and exact description of the invention, such as will enable others skilled in the art to which it app pertains to make and use the same.

This invention relates to turnbuckles and has for its primary object the production of means for facilitating the manipulation thereof.

In practice it frequently happens that auxiliary devices of various kinds are employed to procure the necessary leverage in rotating turnbuckles of this character. These supplemental devices are not always available however, and when used are found in practice to unduly strain, twist and otherwise impair the proper operation of the turnbuckle.

My present invention has been designed to overcome these difficulties and has for an object the production of a novel operating device carried by said turnbuckle and including a projecting handle capable of being moved into an operative position, and subsequently withdrawn therefrom.

Another object of my invention is to produce a turnbuckle provided with a pivoted operating handle mounted for longitudinal swinging movement with relation to the supporting frame of the turnbuckle, and adapted to be extended radially or withdrawn to a plane substantially parallel with the aforesaid supporting frame.

With these and other objects in view the invention further consists in the construction and comparatively simple arrangement of the several parts hereinafter described and pointed out in the appended claims.

In the accompanying drawings wherein similar reference characters designate corresponding parts in the several views:—

Figure 1 is a view in side elevation of my improved turnbuckle showing parts thereof in section, and the collapsed or withdrawn position of one of the operating handles in dotted lines;

Fig. 2 is a vertical transverse view on the line 2—2 of Fig. 1;

Fig. 3 is a detail perspective view of 55 bracket in which the operating handle is pivotally mounted.

Referring to the drawings, the turnbuckle is shown as comprising a supporting frame or yoke 1 formed of parallel side bars 2 60 united at their ends as at 3 to form bearing supports for the end engaging devices 4. The engaging devices may be in the form of the open links or hooks 5 as shown, or may be of any other approved construction 65 to facilitate the interpositioning of the turnbuckle as will be understood.

The usual screw 6 is provided as the means for moving the supporting frame with relation to the engaging devices. This screw 70 may be of single construction as shown, or two of these screws may be utilized, each interconnected with their respective engaging device.

The operating device is carried by the 75 supporting frame of the turnbuckle and includes a handle 7, pivotally mounted at 8 in the bracket 9. This bracket 9 is formed with side extensions 10 constituting the journal support for the pivot pin 11, and 80 also serving to prevent lateral movement of the operating handle. The said bracket also permits of the handle swinging longitudinally of the supporting frame as indicated by the dotted lines in Fig. 1. 85

The handle 7 may be formed of appropriate material, and is provided with a relatively large flat portion 12 having an opening therein for receiving the pivot pin 11. A shoulder 13 is provided on the handle and 90 serves as a limiting stop when the handle is moved to extended position. This shoulder prevents the handle from swinging in but one longitudinal direction as will be understood. 95

In use the turnbuckle is attached to the apparatus with which it is to be used, and the handles 7 are extended as shown in Fig. 1. By means of these handles an increased leverage is obtained and the manipulation 100 of the turnbuckle becomes comparatively easy.

The pivot pins are shown as fixed in the bracket 9, but it will be understood that removable pins or bolts may be substituted 105 if it is desired to provide readily detachable handles 7.

The uses to which my improved turnbuckle

may be applied are many and I do not limit its application to any particular apparatus, but for example I have found it particularly useful in connecting with a surgical apparatus set forth in an application Serial Number 427,740, filed by me December 2, 1920.

Various changes in the construction and arrangement of the several parts may be resorted to and I do not limit myself to the exact disclosure of my invention as set forth herein.

I claim:

1. A turnbuckle comprising a supporting or connecting frame, an engaging device carried by said frame, means for permitting the relative movement of said frame and engaging device, and an operating device including a handle pivoted to said frame and adapted to be swung outwardly whereby the frame can be easily turned.
2. A turnbuckle comprising a supporting frame, engaging devices carried by said turnbuckle, means for moving the engaging devices with relation to the supporting frame, and a projecting operating handle pivotally mounted upon said frame and adapted to be moved from projecting position to a position substantially parallel with the aforesaid supporting frame.
3. A turnbuckle comprising a supporting frame, engaging devices carried by said turnbuckle, means for moving the engaging devices with relation to the supporting

frame, a pivoted handle projecting from said frame and means for pivoting said handle for swinging movement longitudinally of the supporting frame.

4. A turnbuckle comprising a supporting frame, engaging devices carried by said turnbuckle, means for moving the engaging devices with relation to the supporting frame, a pivoted handle projecting from said frame, a bracket for pivotally mounting said handle on an axis extending transversely of the longitudinal plane of the turnbuckle, said bracket having means for preventing lateral and permitting only longitudinal movement of the handle with relation to the supporting frame.

5. A turnbuckle comprising a supporting frame, engaging devices carried by said turnbuckle, means for moving the engaging devices with relation to the supporting frame, an operating handle projecting from said frame, means for pivoting said handle for swinging movement in one direction longitudinally of the supporting frame, and means for limiting the movement of said handle when projected outwardly from said frame.

In testimony whereof I affix my signature in presence of two subscribing witnesses.

SALVATORE FERRAGAMO.

Witnesses:

PETER STORNI,
LOUISE D'ANDREA.
